US0D1094010S

(12) **United States Design Patent** (10) **Patent No.:** **US D1,094,010 S**
(45) **Date of Patent:** **** Sep. 23, 2025**

(54) **PORTABLE WATER PIPE ASSEMBLY**

(71) Applicant: **Puff Corporation**, Los Angeles, CA (US)

(72) Inventors: **Avinash Bajpai**, Aguora Hills, CA (US); **Roger Sayre**, Los Angeles, CA (US); **Dane Wiedemann**, Los Angeles, CA (US); **Amith Diwakar**, Los Angeles, CA (US)

(73) Assignee: **Puff Corporation**, Los Angeles, CA (US)

(**) Term: **15 Years**

(21) Appl. No.: **29/830,298**

(22) Filed: **Mar. 11, 2022**

(51) LOC (15) Cl. **07-01**

(52) U.S. Cl.

USPC **D7/396.2**

(58) **Field of Classification Search**

USPC D7/213, 300.1, 387, 392.1, 393, 394, D7/396.2, 397, 398, 510, 511, 533, 536; D9/417, 435, 436, 439, 440, 447, 449, D9/454; D11/154, 157; D27/100, 103, D27/162, 163, 164, 167, 168, 169, 170, D27/194

Assistant Examiner — Nader Abadir

(74) *Attorney, Agent, or Firm* — Bryan Cave Leighton Paisner LLP

(57) **CLAIM**

The ornamental design for a portable water pipe assembly, as shown and described.

DESCRIPTION

FIG. 1 is a front perspective view of the portable water pipe assembly in its closed state;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a front perspective view of the portable water pipe assembly in its open state;

FIG. 9 is a front view thereof;

FIG. 10 is a rear view thereof;

FIG. 11 is a side view thereof;

FIG. 12 is an opposite side view thereof;

FIG. 13 is a top view thereof; and,

FIG. 14 is a bottom view thereof.

The broken lines form no part of the claimed design. The dash-dash broken lines depict portions of the portable water pipe assembly. The dash-dot-dash broken lines depict the boundaries of the claim.

1 Claim, 14 Drawing Sheets
